UNITED STATES PATENT OFFICE.

MATTHEW THRAVES SHARP, OF LONDON, ENGLAND.

ROLLER-BLIND.

SPECIFICATION forming part of Letters Patent No. 618,441, dated January 31, 1899.

Application filed February 5, 1898. Serial No. 669,248. (No model.)

To all whom it may concern:

Be it known that I, MATTHEW THRAVES SHARP, a subject of the Queen of Great Britain, residing at London, England, have invented new and useful Improvements in Roller-Blinds, (for which I have applied for patents in Great Britain, No. 18,187, dated August 4, 1897, and in France, No. 260,552, dated December 3, 1897,) of which the following is a specification.

This invention relates to improvements in roller-blinds, the improvements having for their object to so construct such blinds that they will admit of ventilation at the upper part of the windows to which they are applied.

In carrying out my invention I form in the blind, near the upper part thereof, an opening or openings, which may or may not be covered with an open fabric or network, the said opening or openings being so placed that when the blind is pulled down to cover the window it or they will be opposite the top part of the window. To the said opening or openings I adapt a flap or shade so arranged that if it be required to cover the opening or openings it is merely necessary to pull the blind down somewhat lower, when the flap or shade will cover the said opening or openings.

It will be obvious that I can adapt my ventilating arrangement to more than one part of the blind.

To enable my invention to be fully understood, I will describe the same by reference to the accompanying drawings, in which—

Figure 1 is a front elevation, and Fig. 2 a section, showing my improved blind applied to a window, the blind being in the position it occupies when the opening in the blind is uncovered; and Figs. 3 and 4 are respectively a back elevation and section showing the blind pulled fully down, the flap or shade being behind the said opening, so as to cover the same.

a is the blind, which in the drawings is shown applied to a window by the ordinary spring-roller *b*.

c is the opening (or there may be more than one) in the upper part of the blind, which said opening may, if desired, be covered with open fabric or network, such as *d*.

e is the flap or shade which I apply to my

blind, this flap being deep enough to cover the opening. It may be permanently attached to the blind or may be detachably connected thereto. The flap is provided at its lower end with lace or other ornamentation *e'* for holding it down and also advantageously with springs *e²* *e²* for bending its lower edge away from the opening *c* when it covers the said opening, as hereinafter described, to allow of ventilation. The springs being flexible can be rolled around the roller when the blind is rolled up. The flap *e* is secured to the face of the blind which is the outer face as the blind is wound upon the roller, as shown in the drawings.

When the blind is pulled down, it will of course be unrolled from the roller *b*, and when the lower edge of the flap *e* leaves the roller, on the under side of the same, instead of following around the roller it will fall down behind the roller and permit the portion of the blind containing the aperture *c* to be unrolled, as shown in Fig. 2. If, therefore, the downward movement of the blind is discontinued when the opening *c* shows at the top, the loose edge of the flap *e* will be held between the roller and the woodwork of the window-casing adjacent to the roller, so that the aperture will appear just below the roller. If, however, the blind is pulled farther down, so as to disengage the loose edge of the flap from between the roller and the adjacent part of the window-casing, the flap will fall forward and conceal the opening *c*, although even in this position the springs *e²* will hold it away from the blind and thus permit the air to pass through the opening *c* for purposes of ventilation.

f is the usual cord for releasing the spring by which the blind is raised.

Having now particularly described and ascertained the nature of my said invention and in what manner the same is to be performed, I declare that what I claim is—

1. A roller-blind for windows comprising a roller, the blind secured at one end to the roller and provided with an aperture therein, and a flap secured along its upper edge to the blind adjacent to the upper edge of the aperture and upon the outer face of the blind as it is wound upon the roller, whereby when the blind is unrolled, the loose edge of said

flap will fall away from the roller and below the attached edge and allow the aperture to be exposed adjacent to the roller and will be drawn around the roller and will fall into position to cover said aperture when the blind is drawn farther down, substantially as described.

2. A roller-blind for windows provided with an open portion adjacent to the upper edge 10 of the blind for ventilation, a closing flap or shade adapted to cover said open portion, and secured to the blind above said open portion, and springs for holding the flap away from the blind, substantially as described.

3. A roller-blind for windows provided with 15 an open portion adjacent to the upper edge of the blind, for ventilation a flap for covering said open portion, secured to the blind above said open portion, and springs secured to said flap and adapted to hold the flap away 20 from the blind, said springs being adapted to pass around the roller when the blind is rolled up, substantially as described.

MATTHEW THRAVES SHARP.
